UNITED STATES PATENT OFFICE.

RUFUS KING, OF PLAINVILLE, MASSACHUSETTS, ASSIGNOR TO BUGBEE & NILES CO.,
OF PROVIDENCE, RHODE ISLAND, A CORPORATION OF RHODE ISLAND.

CLASP FOR BRACELET-CHAINS.

1,117,055.

Specification of Letters Patent. Patented Nov. 10, 1914.

Application filed January 10, 1914. Serial No. 811,343.

To all whom it may concern:

Be it known that I, RUFUS KING, a citizen of the United States, residing at Plainville, in the State of Massachusetts, have invented a new and useful Improvement in Clasps for Bracelet-Chains, of which the following is a specification.

The nature of my invention consists in an improved snap hook for securing the abutting ends of a bracelet to each other, as hereinafter set forth.

In the accompanying drawing: Figure 1 represents a side view of three links of a chain bracelet, one of which is provided with my improved clasp. Fig. 2 represents a plan view of the same. Fig. 3 represents a longitudinal section showing the clasp closed. Fig. 4 represents the same showing the clasp opened, and the links separated.

In the drawing A, A', A represent links of a chain bracelet, the clasp being contained in the intermediate link A'. Each of the links A, A', A, is made of two parallel bars *a*, *a*, which are connected at their ends by means of the cross-bars, *b*, *b*, which pass through the opening of the intermediate link D. The hook clasp C is formed with a spring arm *d*, embracing the pin *e* which forms a stop against the extended movement of the hook, and the parallel bars *a*, *a*, are provided with the cross-stops *f* and *g* which serve to retain the said hook clasp C loosely in place, between the said bars.

The spring arm *d* is provided with the slightly projecting spur *h*, which is adapted to engage the cross-stop *f*, and with the

forwardly inclined projecting spur *i*, the said spur *i* being provided with the finger-nail notch *j* for convenience of manipulation. By pressing downward upon the spur *i* the hook portion *k* may be extended so as to release the opposite end link of the chain, as shown in Fig. 4, and when the clasp C is forced back the projection *h* which springs up behind the cross-stop *f*, serves to firmly secure the clasp in its retracted position, for holding the opposite end link.

I claim as my invention:

In a chain bracelet clasp, a pair of parallel spaced side bars, a pair of superposed cross-bars bridging the space between the side bars and connecting the latter, a stop pin connected to the side bars and located to the rear of the cross-bars, a clasp slidably mounted in the space between the side bars having its outer faces flush with the outer adjacent faces of said side bars and inclosing said stop pin to enable the latter to restrict the extent of outward movement of the clasp and also lateral movement of the clasp relative to the side bars, a pair of projections on the clasp engaging on opposite sides of one of the cross-bars, and a hook on the clasp which extends on the front side of the last named cross-bar and which when in closed position projects within the space between the side bars at the front ends thereof and which is movable to a position beyond the front ends of the side bars.

RUFUS KING.
